UNITED STATES PATENT OFFICE.

JOHN H. DOYLE, OF HILLSBOROUGH, OHIO.

DENTAL LIP AND TONGUE HOLDER.

SPECIFICATION forming part of Letters Patent No. 278,520, dated May 29, 1883.

Application filed October 17, 1882. (No model.)

To all whom it may concern:

Be it known that I, JOHN HARRISON DOYLE, of Hillsborough, in the county of Highland and State of Ohio, have invented a new and useful Improvement in Lip and Tongue Holders for Dental and Surgical Uses, of which the following is a full, clear, and exact description, reference being had to the annexed drawings, forming part of this specification.

10 This invention consists of an instrument for depressing and elevating either the lips or the tongue, as hereinafter described.

In the drawings, Figure 1 is a perspective view, and Fig. 2 an end view, of my lip and tongue holder; and Fig. 3 shows one way of applying the instrument to use.

The lip and tongue holder is formed with a curved plate, A, set nearly at right angles to the handle B, with the edges adjacent to the 20 handle sloping downward therefrom to the ends of the plate. The edge of the plate opposite to the handle is formed with three scallops, a b a, the central one being deeper than the others. The handle B may be formed in one 25 piece or in two, as shown in the drawings, with the ends opposite the plate A made broad and slightly concavo-convex.

The operation is as follows: By holding the handle with the plate A downward, the plate 30 may be inserted between the lower lip and the gums, in which position, when the handle is slightly depressed, the lips will be held apart from the gums, so as to display the lower teeth. By holding the handle with the plate 35 A above the plane thereof, the plate may be

inserted between the upper lip and the gums, so that by elevating the handle the upper teeth will be displayed. By passing the plate into the mouth in the same position as that described for depressing the lower lip, it may 40 be inserted under the tongue if the latter is first turned up against the roof of the mouth by the person operated upon, and in this position it may be pressed gently back against the under side of the tongue, so as to hold it 45 securely out of the way of any operation upon the frenum. By reversing the instrument end for end, the handle may be used for depressing the tongue, while the plate serves in this position as a convenient handle. It will be seen 50 that in the above-described uses the scallops a b a serve to accommodate the muscles and ligaments of the lips and tongue, in order that they shall not be pained during the use of the instrument.

55 This invention is valuable not only to the dental profession, but to surgeons in the treatment of ulcers and other diseases of the mouth.

What I claim is—

The instrument having the curved plate secured to a handle, and having the edges of the plate nearest the handle sloping from the handle, and the edge opposite to the handle provided with one or more scallops, substantially 65 as and for the purposes described.

JOHN HARRISON DOYLE.
